UNITED STATES PATENT OFFICE.

HOWARD N. NAUGLE, OF WAYNESBORO, PENNSYLVANIA, ASSIGNOR OF ONE-FOURTH
TO DAVID R. WISHARD AND ONE-THIRD TO MAURICE HARBAUGH, BOTH OF
WAYNESBORO, PENNSYLVANIA.

CORN PLANTER.

Application filed April 27, 1922. Serial No. 556,978.

To all whom it may concern:

Be it known that I, HOWARD N. NAUGLE, a citizen of the United States, residing at Waynesboro, in the county of Franklin and 5 State of Pennsylvania, have invented certain new and useful Improvements in Corn Planters, of which the following is a specification.

My said invention relates to a corn planter 10 and it is an object of the same to provide a planter with operative means whereby the use of the ordinary check row wire is dispensed with.

Another object of the invention is to provide marking means for indicating the position 15 of the hills transversely of the field.

Still another object is to provide re-setting means for adjusting the tripping mechanism to trip the seed dropping means 20 at the proper time, should this be out of adjustment as frequently happens in making a turn at the end of the field.

Referring to the accompanying drawings which are made a part hereof and on which 25 similar reference characters indicate similar parts,

Figure 1 is a plan of the corn planter with my improvement thereon,

Figure 2 is a side elevation of the same, 30 and

Figures 3 and 4 detail views of the tripping mechanism for the droppers.

In the drawings reference character 10 indicates a U-shaped main frame supported 35 on an axle 11 carried by a pair of wheels 12. At its forward end the U-frame carries an auxiliary frame comprising a pair of transverse members 13 to which the shoes 14 are secured as well as various other conventional 40 elements of the mechanism such as seed boxes 15. A shaft 16 extends transversely of the machine and this shaft has a pin 17 thereon which at each rotation of the shaft is adapted to strike a rounded part 18 on a member 19 (Figures 3 and 4) pivoted 45 on the forward member 13. The member 18 has at one end a reduced portion 20 on which is fixed a laterally projecting pin 21 and this pin at each oscillation trips the dropping mechanism which is of ordinary 50 type. Spring 22 serves to return the member 19 to upper position.

The shaft 16 also is connected by a sprocket 23 to a shaft 24 for stirring up and

portioning out the grain in the seed boxes. 55 A beveled gear 25 on shaft 17 drives another bevel gear (not shown) for moving the hand 26 of an indicating device 27, the face of which bears a number of graduations equal to the distance in inches between 60 two successive hills of corn. Adjacent the indicator is a double ended clutch sleeve 28 loose on the shaft and adapted to engage either one of two clutch members 29 and 30 keyed to the shaft for driving the same. A 65 bent lever 31 pivoted at 32 engages a groove in the sleeve to shift the clutch, the bent lever being connected at one end to hand lever 33 pivoted at 34, the connection being such that movement of the lever 33 lengthwise of the machine causes transverse movement of the lever 31 to actuate the clutch member. Beyond the double clutch is a 70 ratchet 35 also fixed to the shaft and a pawl carrying lever 36 pivoted on the shaft, the 75 lever serving to turn the shaft 16 by its pawl and ratchet connection. At the outer ends of shaft 16 there are a pair of arms 37 adapted to engage with bent end portions of rods 38 projecting through bearings 80 39. At their lower ends these rods are connected to flat tie rods or members 40 which may be fixed at the upper end but which are preferably pivoted at 41 and normally forced downward by means of springs 42 85 attached at one end to brackets 43 fixed on the auxiliary frame and at the other end to brackets 44 fixed to rods 38. By this construction the springs 42 normally force the parts 38 and 40 down carrying with them 90 shoes 45 which may be in the form of shovels or scrapers of any desired type and which as will be understood from the drawing and description normally engage the ground at the sides of the planter and form 95 parallel furrows between the rows. As the shaft 16 rotates the arm 37 will lift the markers each time a hill is planted so that the furrows will have interruptions running 100 across the field and in line with the hills 105 thereby giving a clear indication of the positions of the rows transversely of the field as the interrupted portions of the furrows are or should be in line across the field.

In the operation of the device the hand 105 26 of the indicator, which moves constantly when the machine is running, should be at zero position when the machine is in trip-

ping position to drop the seed for a new pair of hills. In making a turn at the end of the field to start new rows the parts will often be found out of correct position and

5 the extent of such deviation can readily be ascertained as the distance of the hand 26 from unit position should correspond to the distance of the planting mechanism from the first transverse row of hill indications.

10 Supposing this latter distance to be 12 inches then the hand should indicate 12 and if the indication is other than that the clutch 28 should be disconnected and the ratchet lever 36 actuated to turn the shaft

15 16 until the correct number appears on the dial after which the clutch is thrown in and the machine is ready for operation.

Owing to a variety of causes it may happen that the mechanism gets out of line in 20 traveling across the field or a slight deviation from the accuracy may not be noted until a row has been started. In such a case the operator by a quick manipulation of the lever 33 may then suddenly disengage 25 the clutch member 28 from one of clutch members 29 and 30 and slide it over into engagement with the other thereby permitting a slight change of relation between the tripping mechanism and the previously planted 30 transverse rows. Minor conditions of transverse alinement of the hills may thus be corrected by moving the clutch member 28 back and forth once or twice without stopping the machine the advantage of which is 35 apparent.

It will be obvious to those skilled in the art that the machine of my invention may

be modified in various ways without departing from the spirit of the invention, the true scope of which is set forth in the appended claim.

Having thus fully described my said invention, what I claim as new and desire to secure by Letters Patent, is:

In a wheel-supported corn planter having a pair of seed boxes and means for dropping predetermined amounts of seeds therefrom, a transverse shaft adjacent said seed boxes and driven from the supporting wheels of the machine, means on the shaft 45 for operating the dropping mechanism, marking shoes normally contacting with the ground, a tie member associated with each of said shoes, each member being pivoted to the frame and extending downwardly for 50 connection with each shoe, a vertically reciprocable rod fastened to each shoe and extending through a bearing in the frame each rod having a bent over upper end, arms mounted on the shaft adapted to contact 55 with the bent over ends of the rods to reciprocate the rods to move the shoes, and springs secured to the frame and adapted to return the shoes to their normal position adjacent the ground, substantially as set forth.

In witness whereof, I have hereunto set my hand and seal at Waynesboro, Pennsylvania, this twenty-fifth day of April, A. D. nineteen hundred and twenty-two.

HOWARD N. NAUGLE. [L. S.]

Witnesses:

ALF. N. RUSSELL,
C. H. STTELY.

Certificate of Correction.

It is hereby certified that Letters Patent No. 1,480,459, granted January 8, 1924, upon the application of Howard N. Naugle, of Waynesboro, Pennsylvania, for an improvement in "Corn Planters," were erroneously issued to the inventor, said Naugle, and one-fourth to David R. Wishard and one-third to Maurice Harbaugh, both of Waynesboro, Pennsylvania, whereas said Letters Patent should have been issued to the *inventor, said Naugle, one-third to David R. Wishard, and one-third to Maurice Harbaugh, both of Waynesboro, Pennsylvania*, as shown by the records of assignments in this office; and that the said Letters Patent should be read with this correction therein that the same may conform to the record of the case in the Patent Office.

Signed and sealed this 12th day of February, A. D., 1924.

[**SEAL.**]

KARL FENNING,
Acting Commissioner of Patents.
